ILLUMINATED OUTDOOR DISPLAY

Henry A. Thuernau, Clayton, Mo., assignor to
American Displays, Inc., St. Louis, Mo., a cor-
poration of Missouri

Application September 19, 1947, Serial No. 775,101

6 Claims. (Cl. 40—130)

1

This invention relates to improvements in illuminated outdoor displays, and more particularly to advertising displays of the larger, fixedly-mounted, electrically lighted, outdoor types.

It is a known practice to utilize for advertising purposes, many different forms and arrangements of gaseous discharge illuminants, such as so-called neon lights, or variants thereof. In many of these, the tubing is arranged to outline letters or other characters. There has also been known and used to a limited extent, certain transparent lettering, such as glass letters, etc., principally and as far as is known to this applicant, in smaller portable interior displays, such as commercial counter displays or the like. In some of these latter, certain novel illuminating effects are attained by edge illuminants and by refraction effects. There has thus far apparently not been any successful combination utilizing light-transmitting letters, of means utilizing both transmitted light and reflected light, for outlining the letter-forming elements in any manner such that they are attractively visible at great distances, as is necessary with the larger types of outdoor advertising installations. The present invention accordingly has as its principal object, the attainment of this result in a low-cost, easily installed assembly of parts including illuminants.

Yet another object of the present invention is attained in an unusually attractive and novel illumination effect in an assembly for the noted purpose comprising a translucent or transparent character-forming structure, this effect being best realized in a combination including a character illuminated as by transmitted light, and additionally, with a distinct brightening and enlarging effect, lighted by reflected light.

A further highly important object of the invention is attained in increased possibilities for combining different colors of light actually emitted by the display. The many possible combinations will be at once realized when it is noted that the background light reflecting surface may be varied in color and nature; similarly the character element may be varied as to the color of the translucent material from which it is formed, and the choice of illuminant may consist of any of various colors; thus providing by change in any one or several of the noted factors, an almost infinite possibility for color composition and effect.

Yet an additional object of the invention is attained in an improved combination involving a special arrangement of elements, and using a single illuminating means, whereby there is

2

realized a dual effect resulting from both the transmission and the reflection of light from the same source.

Additional objects in improvement of general results, include an improved bracketing and supporting means consisting of units of a material possessing inherent electrical insulation properties, and which is transparent, or at least translucent, and is of such light-transmitting properties as virtually to eliminate the dark areas otherwise apparent from the face of the displays when using older types of support.

Yet another and important objective is found in the provision of a virtually weatherproof, shockproof construction, thereby resulting in virtually no loss of the transparent elements as by breakage either incident to erection of the display, or after same has been in service.

The foregoing and numerous other objects will 20 more clearly appear from the following description of a presently preferred embodiment of the improvements, particularly when considered in connection with the accompanying drawing, in which:

25 Fig. 1 is a front elevational view of one of the character-forming elements shown in the form of a letter, as same would appear when illuminated;

Fig. 2 is a fragmentary sectional elevation as viewed along 2—2 of Fig. 1 and;

Fig. 3 is a fragmentary sectional view along line 3—3 of Fig. 1, Figs. 2 and 3 being considerably enlarged for clarity of structural detail.

Referring now by characters of reference to the drawing of one example selected for disclosure, it is contemplated that the display be erected in situ, utilizing as a primary support for the elements of the display, a substantially vertical planar structure such as the wall W. It will be understood however, that any suitable preferably planar member, such as the face structure of an outdoor advertising bulletin board, may be employed as the primary support.

The surface of structure W desired to be visible along with and as part of the illuminated portions of the display is, by great preference, provided with a highly reflective coating, identified as a reflecting surface RS, this reflecting surface being provided uniformly over the member W, or at least in any case where employed, over those areas rearwardly of the character-forming elements or members, preferably extending somewhat beyond the letters, for reasons hereinafter appearing.

The individual character-forming elements,

sometimes herein called letters, are exemplified by the single letter L of Fig. 1. These are preferably transparent elements of sheet form, and are produced by any suitable practice in shaping any of the well-known or otherwise suitable light-transmitting weather-resistant plastics, such as Plexiglas or Lucite, or other similar materials of light transmitting and shock resistant types.

The character-forming elements are preferably of a generally planar form such as that indicated 10 generally at 10, and in Fig. 1 is composed of the vertical part 11 and horizontal part 12 to form the letter illustrated. It is contemplated as essential to present improvements that the character-forming elements be at least translucent, 15 this term being herein employed as embracing those types of materials which are sometimes referred to as transparent, and sometimes designated as luciform, the term translucent being employed in the sense that light may be transmitted directly through the material with or without a certain degree of either refraction or diffusion.

As a source of illumination, it is preferred that each character-forming element be provided with a light source individual thereto. In the example 25 shown, one or more lines of neon tubing such as indicated at 13, are arranged in a pattern generally conforming to that of the character 10. In the example of Fig. 1, it will appear that the tubing lies rearwardly of the defining margins of the letter, and as viewed from the front or face of the character element, is spaced just inwardly of each margin. Although this arrangement makes for best results, the double line of tubing and exact spacing are not to be regarded as critical, 30 since in some cases a single line of the tubing of any suitable linear form is sufficient to attain the results noted and later to be described in detail.

As will best be seen from Figs. 2 and 3, the line 40 or lines of the linear illuminants are spaced forwardly or outwardly of the reflective surface RS, and are located about an equal distance rearwardly of the character forming element. Thus the reflecting surface RS, the shaped or patterned illuminant 13, and the letter-forming member 10 are located in three spaced parallel planes. It is preferred that the spacing of RS and 10, be about the same as the width of the 45 outlining portion of the letter, e. g. part 11.

It will now have become apparent that it is desirable for best results to avoid any occlusion of the illuminants as seen or viewed by light transmitted through the letters. But for some such provision, there would appear in the bracketing zones a series of darkened areas, resulting from the uneven illumination of the letter elements. Any such result is avoided in the present assembly by the use of transparent or translucent U-shaped brackets arranged in spaced relation behind the letter elements, and in front of the support W. Each such bracket, indicated generally at 14, consists of a pair of spaced planar portions 15 and 16, the former being secured as by a suitable plastic cement (not shown) to the material forming the character 10, and the planar portion 16 supported from structure W as by screws, bolts, expansion bolts or otherwise as indicated according to the nature of the support to attain the requisite anchorage thereto.

In the interest of simplification of erection and assembly, it has been found advantageous to support the gaseous discharge tubing or other form of linear illuminants directly from the U-shaped brackets 14. This is accomplished in the

example selected, through a series of studs or posts 17, such elements being attached to the center or bight portion of each of the U-shaped brackets 14. These studs may each consist of a transparent or translucent center body of a special glass or of a suitable light-transmitting plastic. Each post or stud 17 carries a screw element 20, and the opposite end carries a U-shaped spring clip 21, adapted releasably to grip the glass tubing of the illuminant 13.

The manner of erection and assembly of the elements described, is thought to have been reasonably apparent from the foregoing description, but it may be noted for completeness as being usually desirable as a first step, after selection and formation of the characters such as 10, to attach thereto the U-shaped brackets 14. The dimensions of the legs and bight of each of these are such that the outer leg such as 15 of each of the brackets, may be located flush with the outer margin of the letter-forming element, as indicated by Fig. 3. The U-shaped brackets 14 may be thus located on and attached to the individual character elements prior to erection or final assembly, attachment to the elements 10 being made in a manner best suited to the nature of the plastic material of which the letters are made. In some cases, the plastic of brackets and letters may be warmed, and the brackets fused to the letter elements, thus becoming in effect, integral parts thereof. In other cases, a suitable plastic cement is employed between these parts, preferably being an adhesive of clear or so-called white character, so as to obviate any shadow effects 35 otherwise possibly resulting from the layer of adhesive.

The posts or studs 17 may be attached to the U-shaped brackets at the time of manufacture, or on the job. In either case the line of glass 40 tubing of the gaseous discharge illuminant is inserted between the jaws of, and firmly yet releasably held by the several sets of spring clips 21. Following electrical connections the assembly is 45 then in operative form, each now complete letter being attached to the vertical support such as board or wall W, as through screws, bolts or the like 22.

It will have appeared that the combination of the U-shaped brackets 14 and translucent studs or posts 17 serves to locate the tubing 13 in a definitely aligned relation to the outer margins of the elements 10. This distance inwardly of the letter 50 margins is such that the angle of incidence of a considerable proportion of the light from the tube, considering the surface RS as a reflector, results in an angle of reflection such that the reflected light component is emanated forwardly and just outside of the letter margins. This results in a halo effect or halation, creating a striking illusion of a character of considerably greater than 55 actual size, and presenting a softened outline.

In addition to the reflected light component as described, a considerable proportion of the light from the illuminant 13 is directly transmitted through the translucent or transparent character-forming member 10. It is to be noted as a preference and as shown, that the tubing of itself 60 outlines the letter or other character, and is in substantial registry with the member 10.

The present arrangement affords an unprecedented opportunity for a wide selection of combinations of different colors and for composite color composition, due to possible changes in color of the gaseous discharge illumination, change in 65 color of the character-forming element, and in

the color of the reflecting background. It is greatly preferred of course, that the reflecting surface RS be of some light color, the principal opportunities for color selection being found in the variation of illumination and the transparent letter characters. These combinations may consist of the same color or may be varied according to choice and desired effect, for example, the character-forming member 10 may be red in color with a white gaseous discharge illuminant and a white background, merely to state one of the many possible examples.

It will now have appeared that the device as described by selection of a preferred example, serves fully to attain each of the several objectives above specifically set forth, as well as others implied from the more extended description. Although the device has been described by particularizing a single embodiment, no restriction is thereby intended, inasmuch as numerous variants may be made within the fair scope of the claims hereunto appended.

I claim as my invention:

1. In an illuminated advertising display of outdoor type, a planar support especially provided with a highly reflective surface, illuminants arranged to delineate a predetermined character such as a letter, and located in substantial parallelism to, but spaced outwardly of said surface, and being of elongate or linear form, one or more light-transmitting elements each shaped to define a character such as a letter and arranged in spaced relation forwardly of, and substantially in registering relation to the illuminants, and a series of light-transmitting members of channel section, located marginally of the light-transmitting elements, the sides of each such channel being attached to the reflective surface and the transmitting element, with the illuminant attached to the base of the channel.

2. As an article of manufacture, a bracket for attachment and support of light-transmitting letters as in an outdoor display, the bracket being of a generally U shape and formed of a light-transmitting material of a type to resist impact, and further characterized by a translucent stud element carried by and projected from the bight portion of the U shaped element, the stud element adapted as a support for a tubular type of electric illuminant.

3. An illuminated outdoor advertising display including a planar structure such as a wall or board, coated to provide thereon a highly light-reflective surface, a series of translucent character-forming elements each consisting of a substantially heavy sheet-like body outlined to provide the letters or other characters and spaced from the vertical support, a series of spaced brackets consisting of three connected portions, two of the portions being of planar form and secured respectively to the vertical support and to a marginal portion of the character forming element, a third such portion consisting of a bridge or distance piece connecting the first two said portions, each said bracket being formed of a single piece of translucent, impact and weather resistant plastic material, an arrangement of electric illuminants of tubular type entirely rearwardly of each character-forming element and spaced intermediate the element and the planar structure, the illuminants being arranged in a pattern conforming generally to the outline of each of the said character-forming elements, and in substantial registry therewith in such manner that when the illuminated character-forming element

is viewed from its face, the lines of illuminant tubing appear to lie just inwardly of the margins of the character-forming element, and a plurality of transparent posts or studs, carried by the U shaped brackets and serving therewith to provide a substantially shadowless support for the tubing of the illuminants, said tubing being thereby arranged so that light therefrom is transmitted directly through marginal portions of the several character-forming elements, and portions of the light therefrom are reflected from the coated planar structure to provide an halation effect marginally of each of the character-forming elements.

4. An illuminated outdoor advertising display including a substantially vertical planar structure such as a wall or board, coated to provide thereon a highly light-reflective surface, a series of translucent plastic character-forming elements each consisting of a substantially heavy sheet-like body outlined to provide the letters or other characters, and spaced from the vertical support a distance of the order of the width of the outlining portion of the character, a series of spaced brackets, each of a substantially U shaped form and each consisting of three connected portions, two of the portions being of planar form and secured respectively to the vertical support and to a marginal portion of the character forming element, a third such portion consisting of a bridge or distance piece connecting the first two said portions, each said bracket being formed of a single piece of translucent, impact and weather resistant plastic material, an arrangement of electric illuminants of tubular gaseous discharge type entirely rearwardly of and beyond each character-forming element and spaced intermediate the element and the planar structure, the gaseous discharge illuminants being arranged in a pattern conforming generally to the outline of each of the said character-forming elements, and in substantial registry therewith in such manner that when the illuminated character-forming element is viewed from its face, the lines of illuminant tubing appear to lie just inwardly of the margins of the character-forming element, and a plurality of transparent posts or studs, carried by the U shaped brackets and serving therewith to provide a substantially shadowless support for the tubing of the illuminants, said tubing being thereby arranged so that light therefrom is transmitted directly through marginal portions of the several character-forming elements, and portions of the light from said tubing are reflected forwardly from the coated planar structure to provide an halation effect marginally of each of the character-forming elements.

5. As an article of manufacture, a bracket for attachment and support of light-transmitting letters in an outdoor display, the bracket being of a distinctly angulate U shape including a planar element for attachment to a supporting surface, a second planar element parallel to the first such element and spaced outwardly thereof, together with a third planar portion transversely of and marginally connected to the first and second planar elements, each of said planar elements being formed of a light-transmitting material of a character to resist impact, the article being further characterized by a translucent stud element projected outwardly from the third said planar portion of the bracket, and a metal clip at the outer end of the stud element, the stud and clip being adapted as a support for a tubular type of electric illuminant.

nant, the stud element being located substantially intermediate the first and second said planar elements.

6. An outdoor illuminating display structure for supported attachment to a member provided with planar reflecting surface, said structure including a transparent letter-forming element, a U-shaped bracket of channel form and of transverse section, the bracket being formed of a light-transmitting material of a type to resist impact, one of the sides of the bracket channel being attached to and forming a direct support for the letter element, the other side of the channel of the bracket being attached to the reflecting surface structure, and a translucent stud element carried by and projected from an intermediate part of the bottom element of the U shaped channel bracket, the stud element being adapted

as a support for a tubular type of electric illuminant.
